TENDER STRUCTURE

William L. Lentz, Tuckahoe, N. Y., and William M. Sheehan, St. Louis, Mo.; said Sheehan assignor to General Steel Castings Corporation, Granite City, Ill., a Corporation of Delaware

Application December 14, 1929. Serial No. 414,150
14 Claims. (Cl. 105—234)

Our invention relates to railway rolling stock and consists in a novel locomotive stoker device and more particularly relates to the stoker structure and associated parts on the tender. It has been the practice to wall off a substantial portion of the tender interior and to enclose in this walled-off portion a stoker trough in which a conveyor screw is mounted. The compartment and, usually, the trough have been formed of a number of parts assembled with each other by bolts or rivets in a built-up structure which involved considerable machining of parts to be fitted together and required substantial labor for the assembling operation.

The main object of our present invention is to form a compact, rigid conveyor trough with associated parts in such form that a minimum amount of space will be required for the conveyor device and the destructive forces arising from the severe service to which the conveyor is subjected may be effectively resisted without making the conveyor structure unwieldy and difficult to install or remove. We also desire to eliminate the necessity for the usual stoker receiving compartment in the tender structure by making the trough and associated parts watertight and adapted to be combined with tender elements to increase the water capacity of the tender over and above the capacity usually provided.

These and other detailed objects are attained in the structure shown in the accompanying drawings, in which—

Figure 1 is a top view of a preferred form of our device as applied to a tender frame.

Figure 2 is a side elevation of our trough structure alone.

Figure 3 is a vertical longitudinal section taken through the center of the device on the line 3—3 of Figure 1 and indicating the associated tender structure.

Figure 4 is a front view of the device and tender structure.

Figures 5, 6 and 7 are vertical transverse sections taken on the lines 5—5, and 6—6 and 7—7 of Figure 3.

Figure 8 is a detail section taken on the line 8—8 of Figure 1.

The tender underframe may be of any desired form but we illustrate a preferred frame of the type in which the bottom of the frame forms the bottom of the tank whereby the capacity of the tender is increased and the center of gravity is lowered. This type of frame is disclosed in Patent No. 1,663,036, issued March 20, 1928, to Ashe &

Pflager and includes spaced center sills 1, side sills 2, a bottom web 3, transverse members 4, an end sill 5 and other elements referred to below. The superstructure side sheets 6 are secured directly to the side sills 2 of the underframe and the forward part of the tender is provided with a centrally located fuel compartment, the sides of which are formed by plates 7 and 8 and the bottom of which is formed by elements of our stoker trough device.

The trough includes sides 9 which are vertical in their upper portion and converge downwardly, merging in an arcuate portion 10 which receives the lower half of the conveyor screw 11. Lateral extensions 12 are preferably formed integrally with the upper parts of the trough sides 9 and are provided with flanges 13 at their outer edges to which lower edges of sheets 7 are secured. These extensions 12 are rabbeted, as indicated at 14, to provide surfaces mounting the cover plates 15 and guide strip 16. The outer edges of extensions 12 are braced from the body of the trough by inclined elements 17. At the opposite ends of the trough are lateral extensions, that at the forward end including a rear wall 23 and side walls 24 having flanges 25 for mounting the tank end sheets 26. These parts form means for walling off the space over the draw bar pocket 27, which space should be open to the atmosphere to permit manipulation of draw bar elements.

The lateral extension at the rear of the trough comprises an end wall 20 with sides 28 for attachment of the fuel compartment plates 7 and including flanges 28^a forming a pan-like chamber for receiving the conveyor screw gearing G. The rear wall 20 also includes an integral bearing bracket 18 for mounting the conveyor screw 11.

A rectangular frame 29 projects from the lower portion of wall 20 and is adapted to surround the upper end of an opening 30 provided in the tender frame to permit manual access to the rear of the stoker device and to the gearing G. This frame serves to attach the adjacent edges of the fuel compartment sheets 7 and 8. A removable cover plate 31 is applied to chamber 28^a.

The trough is supported by walls 20 and 23 and by an intermediate member 19. Walls 20 and 23 are wide enough to span the space between the frame center sills 1 and rest upon the latter as well as upon transverse members 4 of the underframe. Member 19 is of restricted width and is supported directly upon that portion of the frame cross member 4^a which extends between the cen-

ter sills 1. It is reinforced by suitable ribs 21 and has a horizontal foot 22 adapted to engage the finished pad provided on the upper face of its supporting member.

5 Projecting laterally from the forward portion of the trough is a bracket 32 provided with a bearing 33 for a drive shaft 34 operated from the locomotive and extending rearwardly through wall 23 to a bearing 35 formed in the wall 20 of the chamber 28. A pipe 36 extends between walls 23 and 20 and preferably is welded to the same, as indicated at W, bracing the wall 23 and wall 20 and forming a housing for drive shaft 34 and excluding water from the same and from the shaft bearings 33 and 35.

10 The forward portion of the structure mounts a casing 38 adapted to enclose the rear end of the forward conveyor unit (not shown) which extends from the tender to the locomotive fire box. A crusher member 39 is mounted on the interior of the forward end of the housing and cooperates with the screw 11 to break up the coal in the usual manner. Members 38 and 39 may be formed integrally with the housing but we 15 prefer to form them separately so that access to the universal joint may be had readily and so that the crusher unit may be replaced from time to time.

20 By forming the parts described in a single unit, preferably consisting substantially of a one piece casting, the structure is so rigid that there will be practically no play between the shaft bearings and we can utilize a single piece of shafting extending throughout the length of the 25 stoker mechanism contained in the tender. This eliminates the necessity of additional intermediate bearings and the provisions of a flexible joint intermediate the ends of the conveyor screw such as usually provided in stoker mechanisms.

30 40 The described structure also forms a water tight cover for the water compartment below it, or a bottom for the fuel compartment above it. Its use will reduce the water capacity of the tender a relatively slight amount and the effectiveness of the tender is increased accordingly. The drying mechanism is simplified and access 45 to the same may be had without disassembly of the tender structure or even draining the water from the tender.

50 We claim:

1. In a device of the class described, a T-shaped structure including a trough with side walls and lateral projections from the upper portions of said walls, said trough and projections forming an imperforate top wall of a liquid compartment.

55 2. In a device of the class described, a trough body having lateral projections from its upper portions, said trough body and projections forming an imperforate top wall of a liquid compartment, and downward extensions on said trough forming a structure for supporting the trough in an elevated position in said compartment, said structure being relatively narrower than said wall.

60 3. In a device of the class described, an integral trough structure including a body with bottom and side walls, and lateral projections from the upper portions of said walls, and downward extensions from the bottom of said trough, said trough and lateral extensions forming an imperforate top wall of a liquid compartment and said downward extensions forming a support for elevating said trough in said compartment, said support being of less width than said body.

75 4. A stoker device for a locomotive tender com-

prising a trough, and a support structure projecting downwardly from the central portion of said trough for mounting the same on a tender underframe, said structure having an over all width substantially less than the width of the upper portion of the trough and the upper portion of the trough being arranged for attachment and support of compartment forming plates.

80 5. In a locomotive tender, a stoker device comprising a trough, relatively narrow support members projecting downwardly from the central portion of said trough for mounting the same on a tender underframe, and projections extending laterally from the upper portion of said trough to form a shoveling floor and the top wall of a water compartment extending beneath the stoker trough.

85 6. A stoker device for a locomotive tender comprising a trough, support members extending downwardly from said trough for mounting the same on a tender underframe, projections extending laterally from the upper portion of said trough to form a shoveling floor, and diagonal braces extending from the sides of said trough to the 90 outer portions of said extensions.

95 7. A stoker device for a locomotive tender comprising a trough, support members extending downwardly from said trough for mounting the same on a tender underframe, projections extending laterally from the upper portion of said trough to form a shoveling floor, and diagonal braces extending from the sides of said trough to the 100 outer portions of said extensions, all of said parts being integral with each other.

105 8. A stoker device for a locomotive tender comprising a trough, members supporting said trough, lateral projections extending from the upper portion of said trough and provided with elements at their outer edges for mounting fuel compartment sheets, and diagonal braces extending from the sides of said trough to said elements.

110 9. A stoker device for a locomotive tender comprising a trough, restricted support members projecting downwardly from the central portion of said trough only for mounting the same on a tender underframe, projections extending laterally from the upper portion of said trough and provided with elements at their outer edges for mounting fuel compartment side plates, and diagonal braces extending from the sides of said 115 trough to said elements.

120 10. In a locomotive tender, spaced longitudinal center sills, a stoker conveyor trough narrower than the distance between said sills and positioned above the level of said sills and between the same, and a transverse member between said sills and supporting said trough.

125 11. In a locomotive tender, spaced longitudinal sills, a stoker conveyor trough positioned above the level of said sills and between the same, a transverse member between said sills and supporting said trough, and elements extending transversely of said trough near the ends thereof and supported on said sills and forming the ends of a water compartment extending above 130 said sills.

135 12. In a locomotive tender, spaced longitudinal sills, a stoker conveyor trough positioned above the level of said sills and between the same, a transverse member between said sills and supporting said trough, and elements on said trough spaced from the sides thereof near each end of the trough and supported on said sills and forming the ends of a water compartment having the trough for a top wall.

13. In a locomotive tender, spaced center sill webs, a horizontal web between the lower portions of said center sill webs and forming the bottom of a water compartment, transverse elements extending between the upper portions of said webs, upstanding legs mounted on said elements, and a stoker trough carried on said legs and forming a part of the top wall of said water compartment.

10

14. A structure as described in claim 13 in which the side walls of the trough are provided with outwardly projecting flanges extending laterally beyond the plane of said sills, there being tank side walls with their lower ends secured to said flanges.
